UNITED STATES PATENT OFFICE.

ARTHUR ERNEST MACDONALD, OF LONDON, ENGLAND.

SPARK PLUG.

Application filed June 25, 1927, Serial No. 201,371, and in Great Britain September 30, 1925.

This invention relates to spark plugs for internal combustion engines, and more particularly to plugs of the type in which an insulator supporting the central electrode is fitted to the body of the plug by means of a part-spherical or like seating adapted to form a gas-tight joint without the use of packing or cement at such seating.

The invention has for its main object to provide an improved seating for the central electrode at the surface where it bears upon the said insulator.

The invention has also for its object to permit slight distortion of the component parts of the plug when subjected to heat, without such distortion affecting the gas-tightness of the two seatings.

A further object of the invention is to allow for slight inaccuracies in the manufacture of the main insulator, such as obliquity of its axis relative to the surface at which the central electrode bears upon said insulator.

The invention is hereafter described with reference to the annexed drawings, in which:—

Figure 1 is a sectional elevation of one form of construction, and Figure 2 is a detail of the electrode. Figure 3 is a similar view of another form of construction.

The form of construction represented in Figures 1 and 2, employs a main insulator *a* enclosed in a recess *b* in the plug body *c* and carried by a ring nut *d* detachably connected to the body *c*, and an outer insulator *e* seated in the ring *d* around the projecting stem *f* of the central electrode, with the usual terminal nuts *g* and a tensioning spring *h* arranged upon its upper end. The main insulator *a* has an annular shoulder *a*¹ of convex bevelled or conical shape at about the middle of its exterior surface, this shoulder fitting in a gas-tight manner against a corresponding concave seating *d*¹ on the inside of the detachable ring nut *d*. The central electrode is provided with a ball member or collar *f*¹, preferably integral therewith, and having an annular face *f*² of part-spherical shape which bears upon a similar surface *f*³ on a small cup-washer *f*⁴ of nickel or other suitable material, forming part of the electrode and bearing against the lower end *a*² of the main insulator *a*. The tension produced in the central electrode stem *f* by the spring *h* at its upper end is transmitted by the collar *f*¹ through the

surfaces *f*² *f*³, which constitute a ball-joint connection between the two parts of the electrode, and thence through the main insulator *a* to the seating of the latter upon the detachable ring nut.

It will be observed that, even if the seating for the cup-washer *f*⁴ is slightly out of truth with the axis of the insulator, proper gas-tight joints are obtained both between the collar *f*¹ and the cup-washer *f*⁴ and between the cup-washer *f*⁴ and the insulator end *a*² by reason of the universal self-aligning effect of the ball joint *f*² *f*³.

In the form of construction represented in Figure 3, the main insulator *a* is arranged in an inverted position as compared with that described above, its shoulder *a*¹ seating upon a corresponding annular surface *c*¹ on the bottom of a ventilated chamber *j* in the plug body. The electrode stem is formed in two parts *f*, *k*, connected by a ball joint, and is partly exposed for cooling inside the chamber *j*. The stem *k* passes down through the upper insulator *e* and has its lower end *k*¹ engaged with a collar or head *f*⁵ terminating the electrode stem *f* and bearing against the top end *a*² of the main insulator; this head is cupped at *f*⁶ to receive the tip of the upper electrode stem *k*, which is pressed down by an elastic disc *m*¹ enclosed in a cap *m* secured to the top of the upper insulator *e*, the tip *k*¹ of the electrode stem *k* thus centering itself automatically in the cup *f*⁶ upon the electrode stem *f*. The upper insulator *e* in turn is held in the plug body by a notched or apertured ring *n* screwed into the top of the chamber *j*, a bevelled shoulder *e*¹ upon this insulator being pressed against the ring *n* by the reaction of the elastic disc *m*¹; the lower end of the upper insulator *e* extends down to the level of the electrode head or collar *f*⁵, so as to allow access of air to this part of the electrode.

In the two constructions illustrated, a self-adjusting or universal motion is allowed by the collar *f*¹ (Figure 1) or the tip *k*¹ of the electrode stem *k* (Figure 3) and the cup *f*³ (Figure 1) or *f*⁶ (Figure 3) of the electrode, which form in effect a self-centering ball-joint so that the gas-tightness of the insulator is not affected by slight inaccuracies in the manufacture.

The insulators employed may be of any suitable material; the main insulator is preferably of fused silica, which allows the formation of gas-tight joints by grinding the

faces into their seatings in the well known manner.

What I claim is:—

A spark plug comprising a body portion having upper and lower seatings therein, an upper insulator in engagement with the upper seating, a lower insulator in engagement with the lower seating, a cupped washer located at the end of the lower insulator remote from its seating and having a concave part-spherical surface, an electrode extending through the two insulators and cupped

washer, said electrode having an annular shoulder of convex part-spherical form adapted to engage the concave part-spherical surface of the cupped washer to form a self-aligning ball joint therewith, and means for exerting pressure through said electrode and ball joint connection to hold the said insulators upon their respective seats to form gas-tight joints. 15 20

In testimony whereof I hereunto affix my signature.

ARTHUR ERNEST MACDONALD.
